DESIGN FOR A FINGER RING

Linus F. Heberger, Rochester, N. Y., assignor to
Metal Arts Company, Rochester, N. Y.

Application October 12, 1936, Serial No. 65,256

Term of patent 3½ years

To all whom it may concern:

Be it known that I, Linus F. Heberger, a citizen of the United States, residing at Rochester, in the county of Monroe and State of New York, have invented a new, original, and ornamental Design for a Finger Ring, of which the following is a specification, reference being had to the accompanying drawing, forming a part thereof.

Figure 1 is an enlarged end elevation of the finger ring showing my new design.

Figure 2 is a plan view of the top of the ring showing my new design.

Figure 3 is a side elevation of the finger ring showing my new design.

I claim:

The ornamental design for a finger ring, as shown.

LINUS F. HEBERGER.
